UNITED STATES PATENT OFFICE.

FRANK POPE AND EDISON E. RANDALL, OF KANKAKEE, ILLINOIS, ASSIGNEES TO
PARAMOUNT KNITTING COMPANY, OF CHICAGO, ILLINOIS, A CORPORATION OF
ILLINOIS.

KNITTING-MACHINE.

1,096,946.

Specification of Letters Patent.

Patented May 19, 1914.

Application filed March 28, 1912. Serial No. 686,770.

To all whom it may concern:

Be it known that we, FRANK POPE and EDISON E. RANDALL, citizens of the United States, and residents of Kankakee, county of 5 Kankakee, State of Illinois, have invented an Improvement in Knitting-Machines, of which the following description, in connection with the accompanying drawing, is a specification, like characters on the drawing 10 representing like parts.

This invention relates to a knitting machine and particularly to the needle and the means for operating it. The needle is of the type in which the hook member and latch 15 member are separate members, that is physically independent and separate from each other, although coacting to perform the required looping functions.

This invention presents a machine embodying this type of needle in which the accurate and desired operation of the needle members is secured at all times.

This invention enables a very fine class 25 of ribbed work to be done. In ribbed knitting, as for example, in the knitting of stockings, the dial needles are supported in a circular course inside of the circular path of the cylinder needles. Hence the number 30 of dial needles which can be employed is limited, one of the main limitations being that fixed by the length of the needle and necessary to enable it to perform its looping function.

By the present invention the movement of 35 the needle necessary to perform the looping function is brought to a minimum and the needle is brought to a minimum length so that a very much larger number of needles may be used in the dial of a rib knitting 40 machine, thus enabling finer work to be performed.

Among the features of the invention by 45 which the desired results are secured are means for frictionally controlling the movement of the latch member, the "set-back" given to the hook of the hook member, and the shape of the face of the hook member, whereby tucking is prevented.

This and other features of the invention 50 will appear more fully from the accompanying description and drawing and will be

particularly pointed out in the appended claims.

The drawings represent so much of a knitting machine as is necessary to a disclosure 55 of this invention.

In the drawings Figure 1 is a central vertical cross section of a portion of a needle cylinder and dial of an ordinary type of knitting machine. Fig. 2 is a view similar 60 to a portion of Fig. 1 showing the parts in different position. Fig. 3 is a top plan view of the needle and a portion of the dial bed in which it slides. Fig. 4 is a side view enlarged of the latch member of the needle. 65 Fig. 5 is a plan view thereof. Fig. 6 is a side view of the hook member of a needle of extremely short length, showing the "set back" exaggerated.

The needle cylinder in which the vertical 70 needles are mounted and operated is indicated at 1, the stud upon which the dial is mounted at 2, the dial bed at 3, and the cam for operating the dial needles at 4. Web holders are also indicated as mounted in 75 the cylinder at 5.

Both the cylinder and dial needles may 80 and preferably should be of the construction of this invention, but for reasons already set forth it is most desirable that the dial needles be so constructed. The description following will relate only to the dial needles and its applicability to the cylinder needles will be apparent without further explanation.

The needle comprises two parts, a hook member 6, and a latch member 7, the latter being shown separately in Figs. 4 and 5. The hook member has a generally similar form to the corresponding member of the 90 ordinary pivoted latch needle, that is to say in so far as it comprises the hook 8, shank, and the butt 90. The shank and butt may be of varying length and shape as in the case of the pivoted latch needle. In the 95 case of this invention, however, where it is desired to perform fine work and place the maximum number of needles in the dial, the shank need not project beyond the butt and the butt may be brought close up toward the 100 hook end, or in fact close up to the slot in the hook member through which the latch

member operates, thus making an extremely short needle having a minimum throw. The hook member of such a needle is shown in Fig. 6. The hook member is slotted at 10 5 near its outer or hook end at about the position of the usual slot of a pivoted latch needle, and this slot is preferably made in the form of a saw kerf entering the hook member from the front or face, so that the 10 end walls of the slot converge toward the back of the hook member and present at the rear surface shoulders 11 and 12. The hook member is mounted to slide longitudinally in a groove 13 formed in the usual manner 15 in the bed, and it is given its longitudinal movement in the usual manner by engagement of its butt 9 with a groove in the cam 4. The latch member is preferably made of sheet metal and of a thickness such as will 20 allow it to move readily within the slot 10 of the hook member. This latch member is shown separately enlarged in Figs. 4 and 5, and comprises a head 14 and a tail 15. A separate longitudinal auxiliary groove 16 is 25 formed in the bed such as the dial bed 3 beneath and centrally of groove 13 so that the groove 13 may be said to be superimposed upon the groove 16. The latch member is provided with cam surfaces 17 and 18 co- 30 operating respectively with the shoulder 11 and the shoulder 9 formed at the upper edge of the forward wall of the slot 10. The latch member is also provided with shoulders 20 and 21 contacting respectively at 35 the required times with the shoulders 11 and 12 of the hook member. The latch member is bent transversely in its tail as is clearly seen in Fig. 5 so that when it is placed in its slot 16 in the body it will be held frictionally therein and will be prevented from 40 movement longitudinally except when it is positively moved by movement of the hook member. This insures the accurate operation of the needle.

45 The cam surfaces 17 and 18 of the latch member are so shaped and the distance between the shoulders 20 and 21 as compared with the distance between the shoulders 11 and 12 of the hook member is such that the 50 movement of the hook member longitudinally under the control of its operating cam results in the required movements of the needle members to secure the proper handling of the yarn.

55 The hook end of the needle is "set back" that is bodily bent or formed back of the general back surface of the shank of the hook member. This increases the slope of the inclined surface 22 leading from the 60 front surface of the hook member into the hook throat and causes the yarn to slide more readily and surely into the hook throat as the needle retracts, and insures against the point 25 of the latch member sliding be-

neath the yarn as the hook member is re- 65 tracted.

The hook member is provided with a hollow or recess at 23 on its face adjacent the incline 22, and the latch member is provided with a similar hollow or recess 24 so that 70 when the needle is in its outward position the yarn will be positioned by this recess and the danger of undesired tucking prevented.

The cam surface 18 of the latch member is 75 so formed that when the hook member is in its retracted position with respect to the latch member the point 25 will be slightly above the hook 8. This obviates the continual tapping of the latch against the hook 80 which is essential in a pivoted latch needle and leads to the crystallization of the metal and the deterioration of that type of needle.

The operation will be apparent from the foregoing description. The needle is shown 85 in its forward position in Fig. 2. While in this position the yarn is fed into the hook 8 of the hook member; the cam 4 then retracts the hook member, the latch member being held against longitudinal movement by its 90 frictional engagement with the walls of the slot 16; during the retraction of the hook member the shoulder 12 contacts with the cam surface 18 and the latch member thus moves into the position shown in Fig. 1 in- 95 closing the yarn in the hook, which slides readily down the steep incline 22 owing to the set back referred to; upon the continued retraction of the hook member the shoulder 21 causes the latch member to be retracted, 100 its frictional resistance with the walls of its slot 16 being overcome. When the hook member is again moved forwardly by its cam the loop just formed slides into the re- 105 cess 23 and the latch is left in retracted position until the shoulder 11 contacts with the shoulder 20 as shown in Fig. 2 and the hook and latch members then move together 110 into outward position with the latch head below the face of the needle member and with the recesses 24 and 23 in coincidence, the shoulder 11 during the first portion of the forward movement of the hook member acting to cam down the latch member into this position. On the next movement of the 115 needle backward after fresh yarn is fed to the hook, the recess 23 insures the last formed loop and the freshly fed yarn being held apart so that the point of the latch may pass between.

120 It will thus be seen that the operation of the needle members is positive and that the longitudinal movement of the needle necessary to take and cast off the loops of yarn is very much less than in the case of the pivoted latch needle, thus enabling a needle operating cam of flatter angle to be used, and consequently diminish the wear and strain 125

upon the needle butt. The action of the members of the needle is positive, the shoulders on the hook member coöperating with the cam surfaces and the shoulders on the 5 latch member to move the latter positively into and out of coöperative position. The frictional engagement of the latch member with its slot prevents any other than the required movement of the latch member.

10 Having fully described our invention, what we claim as new and desire to secure by Letters Patent is:

1. In a knitting machine, a needle comprising a longitudinally slotted hook member, a separate latch member provided with a head and having relative bodily movement to carry the head through the slotted portion of said hook member to cover and uncover said hook, the hook member having 15 an inclined surface leading from its front surface into the hook throat and having the hook end set back from the rear surface of the hook member, whereby the yarn will slide more readily into the hook throat and 20 the point of the latch head will be insured against sliding beneath the yarn as the nee- 25

dle retracts, and means independent of the hook member and located at the rear of the hook member opposite the hook face for creating friction on the latch member. 30

2. A knitting machine needle, comprising a hook member and a separate latch member movable bodily and relatively into and out of coöperative relation, the said hook member having its hook end set back from 35 its rear surface and having a recess in its front surface adjacent the hook throat, the said latch member having a recess in its front surface coinciding with the recess on the front surface of the hook member when 40 the latch member is in retracted position whereby the separation of the last formed loop and the freshly fed yarn is insured.

In testimony whereof, we have signed our names to this specification, in the presence 45 of two subscribing witnesses.
